LEAD AZIDE DETONATORS

Leon Rubenstein and Bertram Campbell, Salt-coats, Scotland, assignors to Imperial Chemical Industries Limited, a corporation of Great Britain

No Drawing. Application November 13, 1946,
Serial No. 709,440. In Great Britain November
26, 1945

3 Claims. (Cl. 52—4)

1

The present invention is concerned with improvements in or relating to lead azide detonator primary initiating compositions and to the production of lead azide detonators containing the improved compositions in compressed form as a primary initiating charge.

The object of the invention is to improve the cohesive properties of said compositions when compressed into detonators, whereby the hazard associated with the handling of lead azide detonators, more especially during the manufacture of lead electric detonators, may be minimised.

Owing to the poor binding properties of lead azide under compression it is a frequent practice to include a small proportion of tetryl in lead azide detonator primary initiating compositions but it would be desirable to effect a further improvement over that obtained with tetryl, in the binding properties of primary initiating compositions comprising lead azide.

We have now found that satisfactory detonator primary initiating compositions comprising lead azide having improved cohesive properties when compressed into a detonator are obtained by the inclusion in the compositions of a small proportion of what may be termed "ultra-short fibre" nitrocellulose.

The present invention thus comprises detonator primary initiating compositions comprising lead azide and including a small proportion of an "ultra-short" fibre nitrocellulose distributed in admixture through the composition. The invention also includes the application of said compositions in the production of detonators and the resulting detonators containing the compositions in compressed form as their primary initiating charges.

By "ultra-short fibre" nitrocellulose as defined herein we mean nitrocellulose fibre having a length between 30 mu and 250 mu, and preferably between 50 mu and 150 mu. "Ultra-short fibre" nitrocellulose is preferably prepared by subjecting nitrocellulose to viscosity reduction treatments sufficiently intense to bring its viscosity as measured in a concentration of 40 gm. in 100 cc. of aqueous acetone made by mixing 95 cc. acetone with 5 cc. water (aqueous acetone of specific gravity 0.8097 at 20°) between the limits 0.3 and 0.5 c. g. s. units at 20° C. The "ultra-short fibre" nitrocellulose so prepared may advantageously contain a stabiliser, such as calcium carbonate incorporated with it to the extent of about 0.5 to 1%, since it must conform to existing requirements for stability.

The amount of "ultra-short fibre" nitrocellu-

lose may advantageously be from about 4 to 12% by weight of the primary initiating composition. "Ultra-short fibre" nitrocellulose may advantageously be mixed with the lead azide and any other ingredients of the composition in the dry way.

The "ultra-short fibre" nitrocellulose may for instance be prepared by directly kiering a fibrous nitrocellulose under pressure until the required fibre length is attained, and then washing the product, but other methods of viscosity reduction than pressure kiering also available, for instance a treatment with boiling dilute aqueous ammonia at ordinary pressure with subsequent bleaching treatment at raised temperature and stabilisation by water boiling. Thus a 10% slurry in a dilute (0.3%) ammonia solution may be made from an industrial nitrocellulose of 12% nitrogen content and a viscosity is measured in a solution containing 40 grams nitrocellulose in 100 cc. of aqueous acetone as aforesaid of about 10 c. g. s. units, the ammoniacal nitrocellulose slurry being boiled at atmospheric pressure for about 16 hours nitrocellulose being then drained, washed and subjected to successive boiling treatments of about 2 hours duration in hypochlorite solution containing 2% available chlorine with an interposed washing treatment, whereby the viscosity is reduced to about 0.4 c. g. s. units. The nitrocellulose is again washed and stabilised by giving it about 4 successive water boilings, each of 4 hours duration. The yield amounts to about half the original weight of the nitrocellulose. In loading the detonator the lead azide-nitrocellulose composition is introduced on to the top of a secondary initiating charge of, for example, tetryl, compressed in the copper or aluminum detonator and compressed into the detonator at the usual pressure employed for loading lead azide primary initiating detonator charges.

The invention is further illustrated by the following examples in which the parts are parts by weight:

Example I

45 Lead azide 64.8 parts, aluminum powder 2.8 parts, lead styphnate 27.6 parts, "ultra-short fibre" nitrocellulose containing a half per cent of its weight of calcium carbonate 4.8 parts. The detonating composition is made by dry mixing. 50 For the manufacture of detonators it may be introduced on top of a secondary initiating charge of tetryl compressed in the copper or aluminum detonators and compressed into the detonators at the usual pressure employed for loading lead azide primary initiating detonator charges.

3

Example II

The procedure and the ingredients are the same as in Example I, but they are present in the proportions lead azide 80 parts, aluminum 1 part, lead styphnate 12 parts, "ultra-short fibre" nitrocellulose 7 parts.

Example III

The procedure is the same as in Example I and II, but composition of the primary initiating charge is lead azide 90 parts, "ultra-short fibre" nitrocellulose 10 parts. In this case an initiating charge of a deflagratable material may advantageously be compressed over the primary initiating charge.

We claim:

1. A detonator primary initiating composition comprising a mixture of lead azide and from 4 to 12 percent of fibrous nitrocellulose, the fibre length of the nitrocellulose being between the range of from 30 to 250 microns.

4

2. The detonator primary initiating composition claimed in claim 1, wherein the fibre length is from 50 to 150 microns.

3. A detonator assembly containing as the primary initiating composition a compressed mixture of lead azide and from 4 to 12 parts by weight of fibrous nitrocellulose, the fibre length of said nitrocellulose being within the range of 30 to 250 microns.
